LAMP SHADE

Filed Sept. 21, 1931

UNITED STATES PATENT OFFICE

JOSEPH H. ALLEN, OF CHICAGO, ILLINOIS, ASSIGNOR TO INLAND GLASS WORKS, INC.,
OF CHICAGO, ILLINOIS, A CORPORATION OF ILLINOIS

LAMP SHADE

Application filed September 21, 1931. Serial No. 563,957.

This invention relates to lamp shades and particularly lamp shades or globes used for street lighting purposes. More specifically, the invention relates to lamp globes of the type which are used for shading the lamps at posts, more especially at street intersections, and which lamps are provided with the names of the intersecting streets, the names being rendered legible both at night and during the daytime.

The primary object of the invention is to provide a new and improved lamp shade preferably in the form of a globe having a portion provided thereon for receiving a resilient band upon which a street name is carried or printed, the globe being constructed and arranged to engage the band or strip so that the band or strip will be sprung in position due to the resiliency of the band or strip and also held in position by the particular formation of the globe, said strip or band being adapted to be mounted inside of the globe and thus protected from the elements.

Another object of the invention is to provide an improved lamp globe which has a downwardly tapered circumferential portion to provide a tapered circumferential groove into which a circular conical band name carrying strip may be arranged, the band being resilient and adapted to be held in proper contacting position with the globe by means of the resilient characteristic of the band.

A further object of the invention is to provide a street carrying indicia arranged inside of a lamp globe for the purpose of protecting the indicia from weather, the globe being provided with a tapering annular groove into which a conical resilient band is arranged, gravity tending to hold the band in tightened position in the groove.

A still further object is to provide a translucent lamp globe having an annular transparent portion formed thereon against which transparent portion a translucent band carrying street names is arranged, whereby the transparent portion will have the appearance of being translucent the same as the band of the globe, but permitting the street names on the band to be clearly seen through the transparent portion of the globe.

The accompanying drawing illustrates a selected embodiment of the invention and the views therein are as follows:

Fig. 1 is a detail sectional view of the improved lamp globe showing its construction and the manner in which the name carrying strip or band is carried by the globe.

Fig. 2 is a detail elevation of the improved globe showing the shaded and translucent parts thereof, but having the name carrying band or strip omitted.

Fig. 3 is a detail perspective view of the name carrying band or strip.

Fig. 4 is a view similar to Fig. 2, but having the name carrying band or strip arranged therein.

Fig. 5 is a detail perspective view of the name carrying band or strip showing the manner in which the same can be deformed or bent for the purpose of inserting the same in position in the globe.

The shade or globe 6 may be molded out of glass and comprises an upper globular portion 7, a lower supporting connecting flange or neck 8, and an intermediate circumferential part 9, the circumferential portion or part 9 being integrally connected to the globe 7 and the neck 8, as indicated at 10 and 11 respectively. The connecting portion 10 is so arranged that the rays from the lamp 12 will not be intercepted and cast a shadow on the circumferential portion 9. The circumferential portion 9 extends outwardly a predetermined distance beyond the outer edges of the globe and neck to provide a recess or chamber 13 extending circumferentially about the entire globe on the inside thereof for the purpose of receiving a band or strip 14, which band or strip is for the purpose of displaying street names. The street names may be applied to the band or strip in any particular manner, but in the present embodiment they are shown as being painted on the outer side 15. The entire globe 6, with the exception of the circumferential portion 9, is preferably treated as by frosting, spraying, or otherwise, in order to provide substantially non-glaring, light diffusing characteristics, while the circumferential portion 9 is left substantially clear and sufficiently translu-

cent 95

100

cent, as indicated at 16, so that the characters 17, making up the street names on the band 14, may be easily seen through the transparent portion 16.

5 It should be understood that when I use the term globe, I do not necessarily mean a lamp shade of spherical form but any shell-like lamp shade is included in the term.

The band or strip 14 is made of flexible 10 material, such as celluloid, and is sanded or otherwise rendered translucent, as indicated at 18, so that, when the band is inserted in the chamber 13, the translucent band will be seen through the transparent portion 16 of the 15 globe, thus giving the appearance that the entire globe, including the circumferential portion 9, is translucent. However, the transparency of the portion 9, 16 permits the characters 17, painted on the band 14, to be legibly and easily seen. The band 14 may 20 comprise a plurality of strips 19 and 20 fastened together, as indicated at 21, or the band may be made from a single strip of material, as desired. The band is made conical, as clearly 25 shown in Fig. 3, and conforms with the conical side walls 22 of the circumferential transparent portion 9, 16. Due to the resilient characteristics of the band, the band will tend to hub the inner surfaces 23 of the side walls 30 22 to bring the outer surface 15 and the characters 17 of the band tight against the walls, permitting the characters 17 to be legibly and clearly seen through the transparent portion 16. Due to the inclination or conical formation 35 of the side walls of the transparent circumferential portion and the inclination or conical formation of the band or strip 14, there is a tendency of the band to drop downwardly by gravity and thus tighten the band 40 in position, causing the outer surface 15 of the band to hug snugly the inner walls 23 of the transparent portion.

The distance between the upper and lower walls 24 and 25, Fig. 1, of the chamber 13 45 may be slightly greater than the vertical dimension of the band, thus permitting the resilient band to have a slight play in the chamber 13. However, when the band is in position a certain length of time, the band 50 is free to drop down a predetermined distance until it is supported on the ledge 26 of the wall 25.

The band 14 is thus held in tight contacting 55 relationship with the transparent portion of the globe due to the normal expansible characteristics of the expansible band which tends to expand and hug the side walls and also tends to drop downwardly and tighten itself in position.

60 A globe constructed in accordance with this invention is highly efficient and at the same time presents a pleasing appearance. A translucent globe, especially if frosted, usually gives what may be termed a milk-white appearance, and by selecting a sepa-

rate, detachable sign strip, the background of which is of the same tint or color, and arranging this strip behind a transparent portion of the globe, the appearance of the combined globe and name strip is uniform 70 throughout. In employing this arrangement it is not apparent that the name strip is a separate, removable thing. Being of the same tint as the body of the globe, the globe presents the appearance of having the street 75 name or other indicia painted directly on either an inner or outer surface of the globe.

Indicia painted upon a sign is more perfect and pleasing than indicia stenciled in a sign, because the characters may be whole, instead of being interrupted, after the typical manner of a stencil. If paint is applied to the outside surface of an outdoor article, such as a lamp globe, rain, hail, frost and dust 80 will cause the paint to deteriorate, but, by employing the teachings of the present invention, the indicia may be on the inside of the globe, and hence completely protected from the weather. If the entire globe were 85 tinted or pigmented, and the indicia were painted on the inside, it is obvious that the indicia would not be clearly visible, because it would have to be seen through the tint or pigment. In the present construction, however, the part 9 is clear or transparent as indicated at 16, forming a window through 90 which the indicia on the strip may be seen. The indicia is not dimmed in any way, thus in the daytime, particularly when the lighting is from the outside of the globe instead of the inside, the indicia stands out much more clearly than it would in a construction wherein the glass surrounding the indicia was frosted or contained a pigment. Thus a 95 globe embodying the invention has the appearance, coloring, and characteristics of a single unitary and uniform article both when lighted from the outside, as in the daylight, or lighted from the inside.

The indicia may be complete and positive, 100 and darker than the background, in contrast to stencilling, being protected from the weather, and is as clearly visible as if it were applied on the outside of the article.

The length of the indicia carrying band or strip is considerably greater than the peripheral distance about the opening whether the opening be circular or polygonal, and in accordance with the invention the transparent portion 16 may be made either circular, 105 oval, or polygonal.

The entire globe, with its cooperating band or strip, has the external appearance of being entirely translucent, due to the fact that that part of the band which shows through the transparent portion of the globe is also made translucent. However, by providing the transparent portion on the globe, the black characters 17 on the band can be legibly 115 and clearly seen. The characters are legible 120 and clearly seen. The characters are legible 125 and clearly seen. The characters are legible 130

during the day because the black characters are directly against the transparent walls of the globe, while at night the black characters are legible because the lamp 12 will illuminate the entire globe, permitting the light rays to pass through all portions of the globe except the black characters on the band.

The globe is ornamental in appearance and houses the name carrying band, thus protecting it from the elements. The band is easily removed and replaced, thereby eliminating the necessity of removing and replacing the entire globe should the street name become illegible or the names of the streets be changed. Also, costs are reduced considerably when new street lamps are installed, as the globes can be placed on their standards, and, after the entire installation is complete, the bands may be made elsewhere and then inserted in position, it being easier, cheaper, and more convenient to carry and distribute the bands than it would be to distribute the globes marked at particular points.

The invention provides a one-piece clearly legible name carrying band or strip which is so constructed and arranged that this strip with the name carrying indicia may be inserted easily and readily in the small opening provided in the globe.

The invention provides an attractive, ornamental lamp globe constructed with a transparent portion so that the characters designating the streets may be readily and legibly seen and which houses the band or strip, thus protecting it from the weather.

Changes may be made in the form, construction, and arrangement of the parts without departing from the spirit of the invention or sacrificing any of its advantages, and the right is hereby reserved to make all such changes as fairly fall within the scope of the following claims.

I do not herein claim the broad subject-matter of invention relating to the mounting of sign-carrying means within lamp shades as set forth in my co-pending application, Serial Number 512,857, filed February 2, 1931; nor the subject-matter of invention relating broadly to the mounting of the edges of sign cards in a groove as set forth in my co-pending application, Serial Number 526,944, filed April 1, 1931.

The invention is hereby claimed as follows:

1. A lamp shade comprising an envelope having an offset peripheral portion, defining an inwardly opening groove on the inside of the shade having a transparent wall portion, and a name-carrying member comprising a continuous band mounted in said peripheral portion behind the transparent wall portion of said shade.

2. A lamp shade comprising a translucent portion and a relatively transparent portion,

a translucent member arranged behind the relatively transparent portion, said translucent member having a predetermined translucence and color bearing a desired relation to the color and translucence of the translucent portion of the lamp shade and indicia formed on said member in position to be viewed through the relatively transparent portion of the lamp shade.

3. A lamp shade having a continuous resilient name band arranged in the shade, said shade having means forming an internal groove therein for supporting the band in position on the interior walls thereof.

4. A lamp shade having a continuous indicia carrying band removably mounted on the interior walls of said shade, the shade being formed with means providing an abutment within the lamp shade for supporting the band in place upon the interior walls of the lamp shade.

5. A lamp shade, said shade being provided with a transparent downwardly tapered portion, and a resilient name carrying band conforming with the shape of said portion and confined therein by the resiliency of the band.

6. A lamp shade having a transparent downwardly tapered portion integral with said shade, and a tapered continuous band conforming with the taper of the transparent portion, said band being resilient, thereby causing the band to spread and contact against the inner walls of the tapered portion of the shade.

7. A lamp shade having an inner circumferential flange integral with the shade and forming an internal recess, and a circular name carrying band arranged inside of said shade in said recess and contacting with the inside walls of said circumferential flange.

8. A lamp shade having a transparent circumferential portion having downwardly tapered walls integral with the shade and forming an internal recess, and a tapered continuous band conforming with the taper of the circumferential portion, said band arranged in said circumferential portion and maintained in position therein by the resilient action of the band.

9. A translucent lamp shade having a transparent downwardly tapered circumferential portion integral with the shade and forming an inner circumferential groove, and a tapered continuous band conforming with the taper of the circumferential portion, whereby the band will tend to lower itself by gravity and be tightened in position in the circumferential groove.

10. A translucent lamp shade, said shade being provided with a transparent downwardly tapered portion, a resilient name carrying band conforming with the shape of said portion and confined therein, whereby the resiliency of the band will cause the

band to press against the face of the transparent portion.

11. A lamp shade comprising an envelope having a light diffusing portion, a circumferential portion integral with the diffusing portion, a supporting neck integral with the circumferential portion, a name carrying band in said circumferential portion, and means to illuminate the interior of said shade, 5 said circumferential portion being connected to the diffusing portion by a reversed curve portion whereby the lamp in the shade will throw light rays through the circumferential portion and not cast any shadows against the circumferential portion or the band.

12. A translucent street lamp having a circumferential portion projecting a pre-determined distance therefrom and providing a chamber inside of the shade, and a 20 resilient name carrying member insertable in said inner chamber and removably confined in place by the resilient characteristics of the member.

13. A shade having a peripheral channel 25 forming a shoulder extending inwardly of the shade, a continuous sign strip of greater length than the periphery of the shoulder whereby the strip when in place will be retained in position on the shoulder, the strip being flexible to enable it to be readily inserted or removed and when in place to utilize the resilience of the strip to keep the same pressed snugly against the walls of the lamp shade above the peripheral shoulder.

14. A shade having a peripheral portion comprising an inwardly extending ledge and an outer wall extending from said ledge, and an annular resilient strip arranged inside of the shade behind the wall and supported by 40 said ledge and pressed against the outer wall adjacent the ledge by the resilience of the annular strip.

15. A shade having a peripheral portion comprising an inwardly extending ledge and 45 an outer wall extending upwardly and outwardly at the edge of said ledge, and an annular resilient strip arranged inside of the shade and pressed against the inside face of said upwardly and outwardly extending wall by the resilience of the strip.

16. A shade having an inwardly extending ledge and an outer wall extending from said ledge, a strip arranged inside of the globe and bearing against the inside face of 55 said wall, said strip being resilient, indicia on said strip, said wall being transparent whereby the indicia on the strip may be seen through the transparent wall.

17. A translucent shade having a transparent portion, a strip arranged inside of the shade and arranged behind the transparent portion, indicia carried by said strip, the strip being translucent and substantially the same color as the translucent shade.

18. A translucent shade, a transparent por-

tion on said shade, a strip supported inside of the shade and adapted to be seen through the transparent portion of said shade, said strip carrying a plurality of characters, the part of the strip between the characters being translucent and the same color as the translucent part of the shade.

19. A lamp shade having a relatively transparent portion and an adjacent colored portion, a name-carrying strip arranged inside of the lamp shade behind the relatively transparent portion, said strip being visible through the transparent portion and having a predetermined color characteristic bearing a desired relation to the color of the colored portion of the lamp shade.

20. A continuous name-carrying band, for lamp shades and the like, made of translucent resilient material and having indicia carrying portions tilted with respect to the axis of the band to present the indicia carried thereon in tilted position, said band having a normal configuration and being compressible to permit insertion thereof through an opening of a lamp shade of size substantially less than the expanded size of the band.

21. Information carrying means for colored lamp shades having a transparent portion, comprising indicia bearing strip of a predetermined color characteristic bearing a desired relation to the color of the shade itself, said strip being relatively flexible and resilient so that it may be readily assembled within the lamp shade behind the transparent portion thereof and which, when inserted, will expand and hug the walls of the lamp shade due to its resilience and create a desired comparative color effect with the adjacent colored portions of the lamp shade when the strip is behind the transparent portion.

22. Information bearing means for lamp shades having transparent portions, comprising a continuous band having contrasting portions formed and arranged to provide indicia means therein, said band being formed of relatively resilient material so that it may be inserted in a lamp shade behind the transparent portions thereof and when inserted will expand within the shade and against the transparent portions thereof due to the resilience of the band.

23. Information display means for lamp shades comprising a continuous band provided with indicia means arranged in groups facing a plurality of directions and the band being formed with one edge longer than the other whereby, when the same is arranged for display in a lamp shade, to present the information for display therein in tilted position to the view of observers facing the lamp shade, said band being of flexible material having a normal expanded configuration and being compressible to permit insertion of the band through an opening of the

shade substantially smaller than the expanded size of the band whereby the band, after insertion, may expand within the shade to hold itself in place.

5 24. Information display means for lamp shades comprising a continuous band provided with indicia means arranged therein in spaced apart groups, said band being formed to present the indicia groups in tilted position and being adapted for mounting on a lamp shade in position therein such that the several indicia groups will be displayed in the lamp shade facing different angular directions, said band being of flexible material having a normal expanded configuration and being compressible to permit insertion of the band through an opening of the shade substantially smaller than the expanded size of the band whereby the band, after insertion, may expand within the shade to hold itself in place.

25 25. Information display means for lamp shades comprising a continuous band provided with indicia means arranged therein in spaced apart groups, said band being formed to present the indicia groups in tilted position and being adapted for mounting on a lamp shade in position therein such that the several indicia groups will be displayed 30 in the lamp shade facing different angular directions, said band being normally curved throughout the portion containing each indicia group, said band being of flexible material having a normal expanded configuration and being compressible to permit insertion of the band through an opening of the shade substantially smaller than the expanded size of the band whereby the band, after insertion, may expand within the shade to 40 hold itself in place.

26. A lamp shade having a transparent portion, a continuous indicia bearing band in said lamp shade, said band being snugly pressed against the interior surface of the transparent portion by its own resilience and integral means formed in the lamp shade for supporting the band in position behind the transparent portion of the shade.

27. A continuous name-carrying band, for 50 lamp shades and the like, made of translucent resilient material and having indicia carrying portions tilted upwardly and outwardly with respect to the axis of the band to present the indicia carried thereon in tilted position, said band having a normal configuration and being compressible to permit insertion thereof through an opening of a lamp shade of size substantially less than the expanded size of the band.

60 28. A lamp shade comprising a translucent wall portion and an adjacent relatively transparent portion, an indicia-carrying member mounted inside the lamp shade behind said transparent portion, said member 5 comprising a band of translucence substan-

tially similar to that of the translucent wall portion of the shade.

29. A lamp shade comprising a translucent wall portion and an adjacent relatively transparent portion, an indicia-carrying member mounted inside the lamp shade behind said transparent portion, the translucent portion of said lamp shade being frosted and the member, comprising a translucent strip of material, having a white color characteristic and a translucence substantially the same as that of the frosted portion of the lamp shade whereby when the member is mounted behind the transparent portion of the shade the entire shade will have the appearance of being uniformly frosted both in the translucent and transparent portions.

30. A lamp shade comprising a translucent wall portion having a distinct coloring and an adjacent relatively transparent portion, an indicia-carrying member arranged inside of said transparent portion, said member being translucent and having a predetermined color characteristic whereby to produce in the transparent portion of the lamp shade a desired color effect.

In witness whereof, I have hereunto subscribed my name.

JOSEPH H. ALLEN.
